United States Patent Office.

CYRUS ROBERTS AND JOHN A. THROP, OF THREE RIVERS, MICHIGAN.

Letters Patent No. 92,475, dated July 13, 1869.

IMPROVED HORSE-POWER.

The Schedule referred to in these Letters Patent and making part of the same.

To all whom it may concern:

Be it known that we, CYRUS ROBERTS and JOHN A. THROP, of Three Rivers, in the county of St. Joseph, and State of Michigan, have invented certain new and useful Improvements in Horse-Powers, of which the following is a full, clear, and exact description, reference being had to the accompanying drawings, which make part of this specification, and in which—

Figure 1 represents a plan or top view of our improved horse-power, in position for operation;

Figure 2, a vertical longitudinal section of the same, at the line $x x$ of fig. 1;

Figure 3, an end elevation of the same;

Figure 4, a vertical section of the bevel-wheel, at the line $y y$ of fig. 1, showing its side roller; and

Figure 5, a view, in perspective, of the bearing for the adjusting-bolt of one of the transverse braces.

The improvements herein claimed consist—

First, in arranging the bed-plate which carries the gearing of the horse-power at an angle upon the frame, in such manner, that when the front wheels are removed, and the front end of the machine lowered upon the ground, the bed-plate shall be parallel thereto, and the gearing in proper position to be operated by the horses.

Second, in a novel arrangement and method of adjustment of the rollers which maintain the bevel-wheel in position, whereby the same is kept truly in line with the pinion of the line-shaft, when in revolution.

Third, in a novel and improved method of securing the machine to the ground, by means of adjustable transverse braces, as hereinafter more fully set forth.

In the accompanying drawings, which show a convenient arrangement of parts for carrying out the objects of our invention—

A represents the angular frame of the horse-power, which is supported upon the front and rear axles A^1 and A^2 and wheels B.

When brought into proper position for operation, the front axle and wheels are removed, and the front end of the machine, which is provided with a transverse bolster, A^3 , lowered upon the ground, as shown in the drawings.

The red lines in fig. 2 show the machine in position for transportation.

An annular metallic bed-plate, C, which carries the gearing by which the horse-power is driven, is secured to sills a upon the frame, above and contiguous to the rear axle A^2 .

The upper surfaces of the sills a are inclined at such an angle to the frame A, that when the front end of the same is lowered upon the ground, the top of the bed-plate will be parallel thereto, and the gearing will

consequently be in proper position to be operated by the horses.

The gearing of the horse-power, not being embraced in the improvements herein claimed, is not shown, with the exception of a central dished bevel-wheel, E, which gears, with a pinion, d , upon a longitudinal line-shaft, D, which is mounted in a bearing at the front end of the frame, and in a box, d , pivoted to an open hanger, C, upon the lower side of the bed-plate.

Couplings D' are secured to each end of the line-shaft, to one or both of which, tumbling-rods may be connected.

By this arrangement, the tumbling-rod, which is connected to the front end of the line-shaft, may be brought very near the ground, so that the horses can walk over it conveniently, and the line-shaft is in proper position for the connection to be made, as soon as the front end of the machine is lowered upon the ground.

In order to prevent the bevel-wheel E from sagging or getting out of line when in operation, friction-rollers e^1 e^2 are arranged upon its upper surface, the one, e^1 , at a point immediately above the bevel-pinion d , and the other, e^2 , at right angles to it, or nearly so.

The friction-roller e^1 revolves on a journal upon the lower end of an arm, e^1 , which passes through a slot in a brace, e^2 , secured to the top of the bed-plate C, being made fast by a set-screw, e^3 , thus rendering the roller adjustable for wear or for different heights of the bevel-wheel.

The roller e^2 rotates upon a journal at the free end of a swinging arm, e^4 , pivoted on a pin, e^5 , on the inside of the bed-plate, and is allowed to rise and fall within proper limits, to follow the rocking of the bevel-wheel, its range of motion being regulated by a pin, e^6 , which can be inserted in any one of a series of holes in a standard, e^7 , secured to the bed-plate or to the transverse brace thereof.

By this arrangement of the adjustable rollers, the bevel-wheel is maintained truly in line with the pinion of the line-shaft, while at the same time a sufficient amount of lateral oscillation is permitted to prevent straining or binding.

A frame, F, is hinged to the rear end of the machine, which, when turned down and locked in position by means of a catch, f , and a rod, f , pivoted to the rear axle, serves as a rest and a means of fastening the rear end of the horse-power to the ground.

When turned up, it can be used, in connection with a similar rack or frame, inserted in slots in the front bolster A^3 , to serve as a support for the rods, braces, &c., of the machine, while in transportation.

In order to provide an efficient method of holding the machine firmly in position while in operation, we employ transverse braces G G, which can be adjusted

to suit unevenness of the ground, in the following manner:

The upper ends of the braces G G' are pivoted to pins g , upon the ends of brackets projecting rearward from each side of the frame A.

The braces G G', extending in opposite directions, transversely to the machine, rest upon the ground, their ends bearing against stakes driven firmly therein.

Slots g^1 are formed in the braces, near the point at which they cross each other, through which a bolt, g^2 , passes, having a nut, g^3 , upon its rear end, by which the two braces may be clamped together, the end of the brace G' being first adjusted to conform to any difference of level in the ground, as shown in red and black lines in fig. 3.

A plate, H, is secured to the lower side of the bracket of the pin g , on the opposite side of the frame to the pivoted end of the brace G.

A slot, h, is formed in the plate H, having a series of recesses at its side, in any one of which may be placed a bolt, h', which passes through a slot in the brace G, and, having a nut upon its rear end, clamps the brace to the plate at any desired height.

By this arrangement, it will be seen that the braces G G' are rendered adjustable, to conform to variations of level in the ground.

The brace G may be made fast to the plate H, and

the brace G' moved upon it, or both moved together, as required.

What we claim as new, and desire to secure by Letters Patent, is—

1. The combination of the frame, the longitudinal line-shaft, and the inclined bed-plate, all constructed and arranged substantially as set forth, for joint operation.

2. The combination, with the bevel-wheel, of the adjustable friction-roller, arranged above the bevel-pinion and line-shaft, and the adjustable side-roller, as constructed and arranged for joint operation, as set forth.

3. The combination, with the bevel-wheel E, of the vibrating friction-roller e' and adjustable stop, as set forth.

4. The combination of the hinged frame F, rod f, and catch f', with the frame of a four-wheeled horse-power, so arranged as to rest upon two wheels when in operation, substantially as set forth.

5. The adjustable transverse braces G G'; for securing the machine in position when in operation, substantially as described, constructed, and arranged.

CYRUS ROBERTS.
JOHN A. THROP.
